UNITED STATES PATENT OFFICE

WILLIAM J. JOHNSON, OF OAKLAND, CALIFORNIA

EDGE-FINISHING MACHINE

Application filed April 4, 1928. Serial No. 267,417.

The invention relates to a machine for finishing arcuately curved edges of manufactured articles made of wood and the like.

An object of the invention is to provide a machine of the character described which is particularly adapted for finishing convexedly curved edges of articles cut from relatively straight grained material.

Another object of the invention is to provide a machine of the class described which is arranged to operate on curved edges formed by cutting grained material in a direction from rather than toward the edge portion which parallels the grain.

Still another object of the invention is to provide a machine of the character described in which a constantly rotating cutter means is carried by a movable carriage.

A further object of the invention is to provide a machine of the character described in which means are provided for automatically disposing an article to be finished in proper relation to the cutters in accordance with the position of the cutter carriage whereby the position of the cutter carriage is the controlling factor in the use of the machine.

A still further object of the invention is to provide for the automatic ejection of a finished article from the machine whereby a subsequent placement therein of an unfinished article may be facilitated.

A more specific object of the invention is to provide a machine of the character described which is particularly adapted for finishing the convex edges of coat hangers cut from wood.

The invention possesses other objects and features of advantage, some of which, with the foregoing, will be set forth in the following specification and in the accompanying drawings in which,

Figure 1 is an end view of a machine embodying the invention.

Figures 2, 3 and 4 are reduced end views similar to Figure 1, but showing the operative parts of the machine in different operative relations to each other and to a hanger to be finished.

Figure 5 is a plan view of the showing of Figure 1.

Figure 6 is a fragmentary view taken on the line 6-6 in Figure 1.

Figure 7 is a fragmentary view taken on the line 7-7 in Figure 1.

Figure 8 is a front view of the showing 55 of Figure 1.

Figure 9 is a diagrammatic view showing the various positions of the cutter carriage for different points in an operative cycle of the machine.

Figure 10 is a fragmentary view of a portion of the structure.

Figure 11 is a fragmentary view taken on the line 11-11 in Figure 8.

Figure 12 is a right side view of the showing 65 of Figure 11.

Figure 13 is a fragmentary view of a portion of the machine.

Figure 14 is a right side view of the showing 70 of Figure 13.

Figure 15 is a fragmentary view showing a hanger-ejecting device of the machine.

Figure 16 is a right side view of the showing 75 of Figure 15; and Figure 17 is a side view of a clothes hanger body.

As herewith particularly disclosed, the mechanism of the device is mounted on a generally rectangular frame 17 formed of angle iron. A horizontal drive shaft 18 is journaled in the frame adjacent the bottom 80 thereof, said shaft carrying a pulley 19 for belted connection to a suitable source of power (not shown).

Pivottally carried on the shaft 18 is a cutter carriage 21, said carriage being mounted 85 at one end of an arm 22 having provided at the other end thereof an elongated bearing 23 engaging the shaft 18 whereby the arm is arranged for movement about the shaft in a plane perpendicular to the shaft axis. The carriage 21, it will be noted, provides a mounting for a pair of arbor shafts 24 and an idler shaft 25 all of said shafts being parallelly related to the axis of the drive shaft 18.

Preferably, and as shown, the shafts 24 are 95 disposed at opposite sides of the arm 22 and at equal distances from the drive shaft axis. As here shown, the shafts 24 and 25 are respectively journaled in elongated bearings 26 and 27 carried on the member 21 and are 100

provided at corresponding protruding ends thereof with pulleys 28 and 29, respectively, said pulleys being disposed in a common plane perpendicular to the drive shaft axis. 5 A pulley 31 is fixedly secured to the drive shaft 18 in the plane of the pulleys 28 and 29 and is operatively connected with the latter by means of an endless belt 32 so connected around and between the various pulleys that 10 the different pulleys 28 will be caused to rotate oppositely at any time, a typical installation of the belt 32 for this purpose being shown in Figures 1 to 4 inclusive.

Cutters 33 and 34 are provided on the shafts 15 24 at opposite ends thereof from the pulleys 28, said cutters being disposed in coplanar relation, with their plane perpendicular to the shaft axis. The cutters 33 and 34 are here shown of equal diameter whereby, by reason 20 of the equal spacing of their shafts from the drive shaft, points of their peripheries nearest the axis of the drive shaft will be equally spaced from said axis. In this manner, a swinging of the arm 22 about the shaft axis 25 will move said last mentioned points of both cutters in a common working arc generally above the top of the frame.

In using the device, an oscillation of the arm 22 through a limited arc is arranged for, 30 and means are accordingly provided for producing such movement. In the present instance, the oscillation of the arm 22 is arranged to be manually effected, and a handle 35 is accordingly provided for the cutter 35 mounting now described. As shown, the handle 35 is in the form of a rod extending from the member 21 adjacent its point of attachment to the arm 22 beyond the plane of the pulleys 28 and 29 whereby an operator may 40 readily grasp the same from the front of the machine for controlling the positioning of the carriage and cutters.

It will now be noted that the present device is particularly arranged for smoothing and 25 rounding the convex edges 36 of wooden clothes hangers 37 which have been cut from flat stock by means of a scroll saw or similar means, said hangers having concave edges 38 of generally the same curvature as are the 50 edges 36, and parallel flat sides 39. The curvature of a hanger edge 36 must be substantially that of the arc of movement of the working points of the cutters in order that the cutters may maintain a working engagement therewith for the entire length of said edge.

Means are provided for releasably holding a hanger in set position for the operation of one or both of the cutters thereon as the carriage 21 is oscillated in the manner described. It will now be noted, however, that in primarily cutting the hangers, the grain of the wood will usually parallel the hanger edges 38 only at the centers of said edges and that 65 the grain of the wood will terminate at these

edges in oblique relation thereto at other points therealong. It is therefore necessary that the cutters be caused to work both ways from the center of the hanger rather than toward said center, and the holding and positioning means are accordingly so arranged as to provide for such operation of the cutters on the hanger.

Essentially and as shown, the hanger holding means comprises a holder 40 in the form of a clamp having cooperating jaws 41 and 42 hingedly connected and arranged to be cooperatively engaged against opposite sides of the hanger. Fixedly mounted across the top of the frame 17 and adjacent the plane of the cutters 33 and 34 is a member 43, said member being here shown in the form of an angle iron having one flange 44 thereof vertically disposed in parallel relation to said plane. Pivotally mounted on the flange 44 at a point thereof substantially vertically above the axis of the drive shaft 18 is an elongated plate member 45 having a curved upper edge 46, the radius of curvature of such edge being substantially that of the hanger edge 36. The plate member 45 is provided in a face thereof with a pair of grooves 47, said grooves extending parallel to each other and transversely of the plate 45 and being arranged to receive ribs 48 provided on the outer side of the clamp jaw 42. Preferably, and as shown, the ribs 48 are arranged for a dovetailed engagement in the correspondingly shaped grooves 47 whereby the clamp 40 is held to the plate and relative movement of the plate and clamp in the line of the grooves is at the same time permitted.

Hanger supporting projections 49 are provided adjacent the bottom of one of the jaws; as here shown, the projections 49 comprise pins extending from the jaw 42 toward the jaw 41 for a distance which is less than the thickness of a hanger. In this manner, like hangers may be successively and similarly positioned in the jaws with their lower edges 100 38 disposed on the pins 49.

It will now be noted that when the holder 40 is in a lower position with respect to the plate 45 which supports it, it will dispose a hanger therein in the plane of the cutters 33 and 34 but below the working path thereof, while a raising of the clamp and hanger on the plate is arranged to dispose the hanger in the path of the cutters.

Referring particularly to the diagrammatic Figure 9, it will be noted that when the carriage 21 is at one extreme end of its arc of travel, as shown at A, the clamp 40 is arranged to be disposed in its lowered position. On the other hand, when the carriage is at or between the points B and D, it is arranged to be fully raised; it thus being clear that the change in position of the carriage is arranged to be effected as it moves between the points A and B in either direc- 120 125 130

tion. Means are accordingly provided for effecting said shift in the disposal of the hanger holding clamp while the carriage moves between said positions A and B thereof, it being noted that Figures 1 and 2 respectively show the carriage in said positions.

Preferably, and as shown, the control of the positioning of the hanger holder 40 is arranged to be automatically effected in accordance with the disposal of the carriage 21. Pivoted at one end thereof to the frame member 43 for movement about an axis parallel to that of the drive shaft, is a cam lever 51 having an arcuately curved lower edge 52. A link 53 connects between an intermediate point of the lever 51 and a point of the plate 43. When the holder 40 is in raised position, the center of curvature of the lever edge 52 is arranged to lie in the axis of the drive shaft 18. A roller 54 is mounted on carriage arm 22 for engagement with the lever edge 52 whereby it supports the lever 51 and holder 40 at all times. As long as the roller 54 engages the lever at the link side of a plane determined by the lever and shaft axes, the movement of the roller along the lever edge 52 will effect no change in positioning of the holder, but if such point of engagement of the roller with the lever shifts to the other side of said plane, then the lever and holder will assume lower positions. The latter condition is arranged to obtain during the shift of the carriage from A to B positions thereof, the relationship being particularly brought out in Figure 11. In this manner the hanger holder is arranged to be raised as the carriage moves from A to B positions, continues its raised positioning as the carriage moves from B to D and back to B, and lowers again as the carriage moves from B to A.

Means are also provided for controlling the relation of the clamp jaws 41 and 42 in accordance with the positioning of the arm 22. Depending from the free clamp jaw 41 below the pivot point thereof is an arm 55, said arm terminating in a member 56 disposed generally parallel to the plane of movement of the arm 22. A bracket 57 extends from the arm 22 toward the plane of the member 56 and carries a roller 58 for constant engagement with said member. The relation of the member and roller is such that while the cutter carriage is between the B and D positions thereof the engagement of the roller with the member so disposes the jaw arm 55 as to hold the jaws 41 and 42 in hanger-clamping relation. That portion 59 of the member 56 however which is arranged to be engaged by the roller 58 when the carriage is between the A and B positions thereof is offset rearwardly out of the general plane of the member whereby the jaws are arranged to separate to release a hanger therein at this part of the working cycle. In this manner, a removal of a fin-

ished hanger and the insertion of another is permitted while the holder 40 is in its depressed position.

It will now be noted that if the hanger should be disposed with the arcuate edge 36 thereof in concentric relation to the working arc of the cutters 33 and 34, both of said cutters would be operative against said edge as the carriage moves from B to D and back to B. If however, the plate 45 is tilted about its pivotal axis, the hanger may be disposed so that but one end thereof lies in the path of a cutter. Since, as hereinbefore indicated, it is desirable that the cutters work from an intermediate point of the edge 36 toward its end, the holder 40 is arranged to be tilted accordingly.

It will now be noted that when the carriage is disposed at the position A as in Figure 1, the forward cutter 33 is arranged to overlie the part of the edge 36 which is parallel to the grain of the wood thereat, which point, in the present instance, is at the center of said edge. In the present embodiment, the tilting of the holder 40 is arranged to be such that the forward end of the hanger is raised during a forward stroke of the cutter carriage and the rearward end of the hanger is raised during the rearward movement of the hanger. This disposal of the holder is effected by tilting the plate 45 about its pivotal axis whereby the lowered portion of the hanger is disposed out of the arc of action of the cutters. In this manner, the forward end of the hanger is engaged by the cutter 33 during a forward stroke of the cutter carriage and the rearward end of the hanger is engaged by the cutter 34 during a rearward stroke of the cutter carriage 21, it being noted that when the carriage is in its forward position, the rear cutter 34 is arranged to overlie the center of the hanger.

In view of the foregoing, means are provided for effecting the required tilting of the plate 45 in accordance with the disposal of the carriage arm 22. Disposed generally beneath and along the lower edge 61 of the plate 45 is a rod 62 carrying forward and rear rollers 63 and 64 respectively. Said rollers are spaced apart a distance slightly exceeding the length of the edge 61 and are mounted in guideways 65 provided on the frame member 43 to permit a limited longitudinal reciprocation of the rod 62. In either tilted position of the plate 45, one of the rollers 63 or 64 is arranged to engage beneath the plate edge 61 while the other lies beyond the end of said edge to permit said tilting. Thus, as shown in Figures 10 and 13, the forward roller 63 is engaged beneath the edge 61 while the arm 22 is in its rearward position whereby the forward portion of the hanger would be raised as is required during a forward stroke of the carriage.

For controlling the disposal of the rollers,

pins 66 extend from the rod 62 into the path of movement of the arm 22, the forward one of said pins being here shown arranged for engagement by the front edge of the arm 22 while the other is arranged for engagement by the rear edge of said arm. The rearward pin 66 is so disposed on the rod that when the rod is in its forward position this pin will be engaged by the arm 22 when the carriage 5 is moving rearwardly and is substantially in the position B. In this manner, the tilting of the plate is arranged to be effected before the forward cutter stroke is made. A similar relation exists for the disposal of the forward 10 pin 66 whereby, when the carriage is in the position D in its forward stroke the rear roller 64 is drawn beneath the plate edge 61 to oppositely tilt the plate. It will thus be clear that the tilting of the holder 40 is arranged to be automatically effected in accordance with the disposal and direction of movement of the cutter carriage.

Depending from the frame member 43 adjacent the forward end of the holder 40 is a bracket 67 carrying at the upper end thereof a bell crank lever 68 having one arm 69 thereof normally disposed to extend horizontally forwardly from the bracket 67 and with the other arm 71 thereof extending upwardly and 25 forwardly from the pivot point of the lever in substantially perpendicular relation to the arc of curvature of the hanger edge 36 thereat. Preferably, and as shown, a screw 72 is provided through the arm 71 to provide a stop 30 against which the opposed end of a hanger 37 is arranged to engage when the holder 40 is in its lower position. A stop 73 extends from the frame member 43 for limiting the forward movement of the lever arm 71. In 35 this manner, the inner end of the screw 72 is arranged to provide an adjustably disposable stop against which the forward end of the hanger is arranged to be disposed by an operator while the holder 40 is depressed and 40 the jaws thereof are open, the adjustment of the stop permitting an exact proper positioning of the hanger in the holder. The screw 72 would, of course, remain set for a particular lot of hangers to be finished in the machine.

It will now be noted that when the holder is in lowered position with a hanger loosely mounted therein and engaging the lever screw 72, a pivotal displacement of the lever is arranged to be effected for ejecting the hanger rearwardly from the holder. Mounted on an arm 74 of the bracket 67 for guided movement against the lever arm 69 is a plunger member 75 having an enlarged head 76 for engagement with the arm 69. Mounted below the plunger 75 and normally engaging the lower end thereof is a second plunger 77. The plunger 77 is resiliently and yieldingly urged to maintain an upper position thereof, 45 in which position it is arranged to normally

support the plunger 75 with the head 76 thereof spaced somewhat from the lever arm 69. In the present embodiment of the invention, the mounting for the plunger 77 comprises an arm 78 of the bracket 67 providing a cavity having the upper and lower walls thereof perforated for the passage of the plunger 77 therethrough. A collar 79 is provided on the plunger 77 within the cavity, and a helical compression spring 81 is engaged about the plunger and between the collar 79 and the bottom wall of the cavity.

Mounted on the bracket 67 below the bracket arm 78 is a bell crank lever 82 having one arm 83 thereof normally horizontal and the other arm 84 depending in a generally vertical direction. The arm 83 is perforated and is disposed for loosely receiving the lower end of the plunger 77 through its perforation. A nut 85 is threadedly mounted on the plunger 77 below the arm 83 whereby it may be adjusted for supporting the lever arm 83 and at the same time permits a raising of said arm. A vertically adjustable extension 86 is preferably provided for the arm 84. Depending from the bracket 67 is a vertically adjustable extension 87 providing an opening therethrough for the reception of the free end of a rod 88 pivoted to the carriage arm 22 and carrying a trip member 89 for engagement with the lever extension 86.

Preferably, the trip member 89 is adjustably disposed on the rod 88, in the present embodiment, said member comprises a flat ring and is engaged between nuts 91 threadedly engaging the rod.

It will now be noted that when the carriage arm 22 is in its rearmost position, as shown in Figure 15, the trip member 89 is arranged to be disposed behind the extension 86, and that said member is arranged to lie in front of said extension when the arm 22 is in its forward position. In this manner, as the arm 22 moves forward, the member 89 will engage the extension 86 and so rock the lever to lift the lever arm 83 along the plunger 77 without affecting the positioning of said plunger. On the return stroke of the rod 88, the engagement of the member 89 with the extension 86 will cause a reverse

rocking of the lever, and so, by reason of the engagement of the arm 83 with the nut 85 on the plunger 77, displace the plunger downwardly against the resistance of the spring 81. The engaging relation of the trip member 89 and extension 86 is such that when the lever is rocked through a considerable angle, the member 89 will move under the extension 86 and so free the lever for a return movement. The action of the spring 81 is arranged to effect a sudden upward movement of the plunger 77, which movement is communicated to the upper plunger 75 which exerts a sudden blow against the lower arm 69 of the lever 68 and so causes the rocking

of the lever 68 to eject the hanger. The ejection operation now described, it is noted, is arranged to take place while the cutter carriage moves from its B position to its A position, the release of the plunger 77 preferably occurring just as the A position is reached.

Briefly the operation of the machine now described is as follows, it being clear that the cutters are arranged to be constantly operated at a proper speed while the machine is in use. When the carriage is at the position A, a hanger 37 is inserted in the holder 40 by the operator who then grasps the handle 35 and swings the carriage 21 forwardly.

By the time the carriage reaches the B position, the holder jaws have been clamped about the hanger and the holder has been raised to dispose the forward portion of the hanger within the working arc of the forward cutter 33. As the cutter 33 reaches the end of the hanger edge 36, the carriage is in the position C, at which time the arm 22 engages the forward pin 66 of the roller rod 62 whereby motion of the carriage from position C to position D is arranged to effect a reversal of the tilting of the hanger. When the carriage reaches the extreme forward position D the rear cutter 34 overlies the center of the hanger edge 36, so that the subsequent backward movement of the carriage to the position B will cause the cutter 34 to finish the rear half of said edge. When the position B is reached, the rear pin 66 of the roller rod 62 is engaged by the arm 22, and between the positions B and A, reversal of the tilting of the hanger holder again takes place, the holder is lowered and opened, and the ejection of the finished hanger takes place in the manner described. This completes a cycle of operations of the machine, it being clear that the various operations respecting the disposal of a hanger with respect to the working path of the cutters are automatically effected in accordance with the position and directing of motion of the cutter carriage.

I claim:

1. In an edging machine for operation on an arcuate edge of an article formed of grained fibrous material, said edge extending generally as the grain of the material and being parallel to the grain at an intermediate point of the edge, a cutter carriage manually oscillatable in a fixed arcuate path, a pair of oppositely rotating and coplanar rotary cutters mounted on said carriage for movement in a common path, a shiftably mounted holder for releasably engaging the article, and means operable by the opposite travels of the cutter carriage to dispose said holder to present the different portions of said edge at opposite sides of said point for engagement by a different cutter.

2. In a machine for finishing a curved edge of an article, a movable holder for the arti-

cle, a cutter carriage reciprocable in a fixed path, a pair of relatively fixed oppositely rotating cutters on said carriage arranged to travel along said edge and in a fixed and common path during the movement of said carriage, and means operable by the opposite travels of the cutter carriage for variably disposing said holder with respect to said path whereby different of said cutters are arranged to operatively engage a common central point of said edge in the different extreme positions of the carriage.

In testimony whereof, I affix my signature.

WILLIAM J. JOHNSON.
